UNITED STATES PATENT OFFICE

114,314

DESIGN FOR AN IRONING MACHINE CABINET

Henry W. Altorfer, Peoria, Ill.

Application December 5, 1938, Serial No. 81,587

Term of patent 14 years

To all whom it may concern:

Be it known that I, Henry W. Altorfer, a citizen of the United States, residing at Peoria, in the county of Peoria, and State of Illinois, have invented a new, original, and ornamental Design for an Ironing Machine Cabinet, of which the following is a specification, reference being had to the accompany drawings, forming part thereof, in which

Fig. 1 is a front elevational view of an ironing machine cabinet showing my new design.

Fig. 2 is a side elevational view thereof.

Fig. 3 is a rear perspective view thereof taken from the top of the cabinet.

I claim:

The ornamental design for an ironing machine cabinet, as shown.

HENRY W. ALTORFER.
